APPARATUS FOR DRILLING TERRESTRIAL BORES

William R. Coleman, Birmingham, Ala.

Application October 29, 1938, Serial No. 237,769

17 Claims. (Cl. 255—5)

The invention relates to apparatus for drilling terrestrial bores, and consists in improvements in structure, by virtue of which the apparatus may be constructed and operated more economically.

In accordance with the aims of the invention, the improved apparatus drills faster; it operates on less power; it is adapted to pump out the cuttings and fluid from the bottom of the well during the drilling operation; it permits accurate study and gauging of the force and speed at which the drill attacks the earth, sand, or rock through which it is working; and it permits coordination of rate at which the tool is fed with the length of stroke, with the number of strokes per minute, and with the intensity of the force with which the tool attacks the terrestrial formation being drilled.

In the accompanying drawings

Fig. I is a fragmentary view, showing in side elevation a manually operated drilling apparatus, in which the invention is embodied; and illustrating in vertical section the bore of a well being drilled;

Fig. II is a view comparable with Fig. I, illustrating an embodiment of the invention in a more elaborate, power operated drilling rig;

Fig. III is a fragmentary view, showing the upper portion of the rig of Fig. II, to larger scale, and partly in side elevation and partly in vertical section;

Fig. IV is a fragmentary view, partly in section and partly in side elevation, of the portion of the apparatus that extends immediately below that which is shown in Fig. III;

And Fig. V is a fragmentary view, in axial section and to still larger scale, of the tool and pump members included in the drilling apparatus.

The apparatus of the invention includes a drilling tool secured to the lower end of a vertical drill-supporting member, which advantageously consists in a tubular drill-rod. The rod and tool assembly is suspended from and supported by an expandable and compressible medium, and as so suspended and supported is adapted to be vibrated vertically, after the manner that a weight freely suspended on a helical spring may be vibrated. In service sufficient power is applied to the drill-rod, to keep the rod and tool assembly in continuous vibration. Each time that the vibrating assembly approaches the lower limit of its range of movement the tool strikes the bottom of the hole being drilled and does its work. As the operation progresses, the drill-rod is rotated step by step, and with each blow the cutting edges of the tool are caused to strike on different lines. And as the drilling continues, the effective length of the reciprocating drill-rod is increased, to provide the essential downward feeding of the tool.

The apparatus may be constructed for either manual or powerful operation. In the case of

powerful operation the expandable and compressible medium referred to may be a gas, while in the case of manual operation such medium may with advantage be replaced by mechanical means, such as a spring.

A manually operable apparatus is illustrated in Fig. I. It consists in a derrick, in this case in the form of a tripod 1 that rigidly supports a head 2 at an interval above the surface S of the earth in which a bore B is to be drilled. One leg of the tripod is provided with a winch 3, from which a cable may extend, and, trained over a pulley 4, provide the hoist essential to the usual drilling operations. The drill or bit 5 of the apparatus is secured to the lower end of a tool-carrier 6; the tool-carrier is secured to the lower end of a vertically reciprocable drilling member, which, as stated, may consist in a tubular drill-rod 7; and the drill-rod is in turn secured to the lower end of a feed-screw 8. A helical spring 9 provides the expandable and compressible medium or means, upon which the drill assembly 5, 6, 7, 8 is suspended, as mentioned above. The spring 9 is secured at its upper end to the tripod head 2 and at its lower end to a nut-block 10 on the feed-screw 8. The spring is adapted to sustain the entire weight of the drill assembly, and such assembly, as so supported by the spring, is adapted to vibrate on the common vertical axis of the spring and drill-rod. The construction and operation are such that, as the vertically vibrating assembly approaches the lower limit of its range of vibration, the drill does its work; that is, the cutting edges of the drill are driven into the earth or rock at the bottom of the well or bore being drilled. In the continuous vibration of the drill assembly, the drill repeatedly attacks and cuts the terrestrial formation at the bottom of the bore. In the course of such operation the drillings or cuttings are removed, the effective length of the drill-rod is increased, and the bore is drilled deeper.

A handle 11 is secured upon the drill-rod 7, and by means of such handle the driller applies sufficient force to maintain the drill assembly in vibration. In the course of such operation the driller turns the handle and rotates the drill-rod through a succession of slight but sufficient angular intervals, to insure that the cutting edges of the drill will not "track." Additionally, it will be understood that the screw 8 rotates in unison with the drill-rod, and that the step-by-step rotation will be in such direction, relatively to the nut, that the screw 8 is fed downward, increasing the effective length of the vertically vibrating drill-rod, and feeding the drill downward apace with its work. As the depth of the well reaches the point where the upper end of the screw 8 approaches the nut 10, the operation is intermittent; the handle 11 is removed from drill-rod 7;

the screw 8 is run up in the nut 10; and an additional section of drill-rod is introduced between the tool-carrier 6 and the screw. This lengthening of the drill-rod with the increasing depth of the bore is a matter that requires no further description to those skilled in the art. The important thing that has been thus far particularly described is the structure by virtue of which vibratory operation of the drill assembly is attained. In this connection it will be understood that the spring (or the other means presently to be described) comprises elastic means that opposes the effect of gravity on the drill assembly. When the drill assembly in its vibratory operation moves downward, the spring stores energy that assists the assembly through the next ensuing upstroke. In this way, the power or effort required to operate the drill is much lower than usual—in some cases the power is one-quarter of that required in the usual drilling apparatus, other things being equal.

The apparatus embodies other features of construction and operation that are important if not essential to the features described above. Turning to the tool-carrier 6, it will be understood that the drill 5 is yieldingly mounted. It will be perceived in Fig. V that the tool-carrier consists in an extensible and contractible structure, including two tubular members 60 and 61 that are telescopically arranged. Organized between such members is a helical spring 62, and such spring is adapted yieldingly to sustain the weight of the tool-carrier member 60 and the bit 5. More specifically, the drill 5 is secured to the lower end of member 60, while the lower end of the drill-rod 7 is, by means of a coupling 63, secured to the upper end of member 61. The body of member 60 is of reduced diameter partway of its length and is arranged within the bore of member 61; integral with member 60 is a casing 64 that terminates at its upper end in a head 65, through which the member 61 extends. The member 61 is at its lower end provided with a flange 66. The coils of spring 62, housed within casing 64, are arranged externally of the telescoping portions of members 60, 61; and the upper end of the spring is secured against movement under torsional stress in a hole 162 in the head 65, while the lower end of the spring is made fast to the flange 66. Thus, when the vibrating drill assembly drives the drill against the work (i. e., against the bottom of the bore being drilled), the members 60, 61 telescopically contract. The spring 62 expands during such contraction of the telescoping members, and the relative movement between such members may in many cases be through such interval that the spring reaches a position of complete expansion, in which case the upper end of the spring may without harm be drawn from the hole 162. This action of the tool-carrier insures that the drill-rod 7 will not buckle, and it prevents other parts of the drill assembly from being subjected to harmful strains. When the reciprocating drill-rod rises, the telescopic members 60, 61 expand, and, as the weight of the member 60 and bit 5 is suddenly picked up by the rising drill rod, the spring 62 acts as a shock absorber, gradually applying the weight of such parts to said drill-rod.

It is further to be noted that the spring 62 is a torsion spring, permitting within the limits of spring tension the rotation of member 60 relatively to member 61. The advantages of the structural refinements described will be appreciated by those familiar with the art, and it is

needless unduly to prolong this specification with a consideration of them.

A further feature of invention consists in forming the telescopic tool-carrier as a pump—the instrumentality that removes the cuttings from the bottom of the bore. The cuttings of rock shale, clay, etc., in which the individual pieces may be as large as $\frac{3}{4}$ " in diameter, are removed during the drilling operation, and thus it is that a "continuous sample" is available.

In adapting the tool-carrier to this secondary utility, I provide both members 60 and 61 in hollow or tubular form. The space within the telescoping members forms an axially extensible and contractible pump chamber C. At the bottom of such chamber, I provide a valve-controlled inlet, while at the top I provide an outlet communicating with the bore of the drill-rod 7. Advantageously, the inlet extends through the body of the drill 5, and opens as close as may be to its cutting edges 51 (Fig. V). In this case the drill is of star-drill construction, including four V-shaped blades 52, backed with plates 53 of relatively hard tool-steel. The said inlet to the pump consists in four passages 50, extending one through the body of each of the four blades 52 into a passage 55 that registers with and forms part of the telescopic pump chamber C. Check-valves 56 and 76 are organized in conventional way with the inlet and outlet of the pump.

The operation of the pump will be readily understood. When the reciprocating or vibrating drill assembly 6, 7, 8, drives the tool 5 against the bottom of the bore B, the descent of the lower telescopic member 60 is suddenly arrested, but the upper telescopic member 61, together with drill-rod 7, continues to descend through, or partway through, the interval between the flange 66 and the shoulder 67. Then, upon the rise of the drill assembly, the telescopic members 60, 61 move back into the positions in which they are illustrated. Manifestly, the chamber C within the tool-carrier is alternately extended and contracted, and is effective, with the valves 56, 76, as a pump. Of course, it will be understood that liquid, if it is not naturally present in the well, will be supplied to provide the essential vehicle for the cuttings and other solid particles to be pumped out. The pump forces the material drawn from the bottom of the well upward through the drill-rod 7, and delivers it above ground to an outlet coupling 12, that connects the screw 8 to drill-rod 7. From such coupling the material is discharged by way of a spout 13 into a sample-box 14, Fig. 1. (The construction of the outlet coupling 12 will be perfectly intelligible upon considering Fig. IV.)

It is important to note that, contrary to common practice, the liquid supplied to the bore B is introduced externally of the drill-rod, while the pump, as said, delivers through the passage within the drill-rod. By virtue of this refinement, a high pneumatic or hydraulic pressure may be established and maintained on the liquid at the bottom of the bore, to assist the pump in its work. Fig. II illustrates that the well or bore B may be provided with a casing, and gas or liquid may be introduced at desired pressure through a conduit 15. In practice the bore B will be deep and the parts 5, 6, 63 will normally be far below ground when this pressure-applying operation is practiced, and, of course, in such event the head 16 of the casing will snugly fit the drill-rod 7, rather than the tool-carrier 6 as shown.

In case the samples obtained by pumping do not

afford the desired information, a core may be taken from the well. A core-tool may be attached to the tool-carrier 6 in place of the drill 5; the drill-rod 7 may be positively rotated (without vertical motion); and the core may be cut and removed in usual way.

Figs. II to IV show the apparatus in more elaborate form and adapted for powerful operation, as is essential in the drilling of deep oil-wells and the like. Save as hereinafter specified, the powerfully operated apparatus embodies the structural features of the manually operated structure already described.

Whereas in the first structure the expandable and compressible means, upon which the drill assembly 5, 6, 7, 8 is suspended for vertical vibration, comprises a spring, in the power operated machine such means consists in a body of gas, conveniently air, confined in a cylinder 17, beneath a piston 18 connected to the screw 8. This confined body of air operates in general the same as the spring, in providing a yielding support upon which the drill assembly may be vibrated. Above and in axial alignment with the air cylinder 17 I provide a steam power cylinder 19 including a piston 20 that is effective in service to keep the drill assembly in vertical vibration.

The power cylinder is secured at its upper end to a head 2a supported on tripod legs 1a; the air cylinder 17 is secured at its upper end to the lower end of the power cylinder, by means of a cylinder head 21; and the walls of the air cylinder extend below its lower head 22, and are vertically slotted, as shown at 23, 24, to provide a slide-way 27 for a slide-head structure 25, 26, presently to be described. A hollow piston rod 28, on which are secured the pistons in both the air and the power cylinders 17 and 19, is at its lower end united to the slide-head structure 25, 26, and the screw 8 extends upward through such hollow piston.

The slide-head structure 25, 26 includes mechanism for effecting the step-by-step turning of the reciprocating drill assembly and the feeding of the assembly downward in accord with the advance of the drill in its work, but inasmuch as the apparatus of the invention does not depend upon the particular form of such mechanism, it is needless to describe the same, more than to say:

1. The slide-head member 26 carries a rotary pinion 29a that meshes with a vertical gear-rack 29 rigidly mounted on slide-way 27; a rotary nut (not shown), in threaded engagement with the screw 8, is rotatably secured in the member 26; during the vertical reciprocation of the drill assembly, the pinion in mesh with the stationary gear-rack rotates first in one direction and then in the other, and the mechanism within the slide-head structure operates to feed the screw 8 downward as need be.

2. The slide-head mechanism coordinates the rate of feed with the intensity of impact of the drill 5 against the work. And such mechanism includes means for indicating on suitable gauges (cf. gauge 30, Fig. II), the intensity of each blow and the depth of cut.

Thus, it will be understood that slide-head structure 25, 26 serves to connect the drill assembly 5, 6, 7, 8 with plunger rod 28; that the assembly is yieldingly borne and adapted vertically to vibrate on the body of air confined beneath piston 18 in cylinder 17; and that the piston 20 in power cylinder 19 is energized, to maintain the assembly in vibration.

More specifically, the power cylinder 19 includes

an exhaust port 31 and a steam inlet port 32 at each end (Fig. III), and in accordance with good engineering practice each set of ports is controlled by a slide-valve 33 (Fig. II); the slide-valves are organized with a suitable valve-gear 34; and a gear-operating rod 35, secured to and reciprocating with the slide-head 25, 26, operates such valve-gear, alternately to open and close the ports in the power cylinder, in such manner as to effect the continuous reciprocation of the piston 20. Steam is supplied to the valve-controlled inlet ports 32 (Fig. III) from a steam line 36 (Fig. II), and the exhaust ports 31 (Fig. III) discharge into an exhaust manifold 37 (Fig. II).
 15 In order that proper coordination of the operating parts of the apparatus may be established and maintained, I provide means for varying the effective length of that portion of the air cylinder which extends below the piston 18, and I also provide for the regulation of the degree of elasticity of the body of air confined therein. The means for varying the effective length of the air cylinder are advantageously hydraulic means, consisting in this case in a hydraulic pump 44 (Fig. III) adapted at the will of the attendant to deliver liquid into a pool P in the bottom of the cylinder, and alternately to remove liquid from such pool. Thus, the depth of the pool P may be increased or decreased, manifestly achieving the desired regulation of the effective length of the air cylinder. The means for regulating the degree of elasticity of the air (without necessarily varying the effective length of the air cylinder) consist in an air compressor 45, communicating through a lead 41 with the air cylinder 17, at a point below the piston 18. Among other desiderata this regulation of pneumatic elasticity and pressure permits the establishment of the desired balance between the pressure of air acting upward on the piston 18 and the force of gravity acting downward on the reciprocable parts.
 20 30 35 40

Another important feature remains for consideration in this specification. It consists in the provision of means for safeguarding the structure in case the drill-rod, or other part, should break and suddenly remove the weight of the drill assembly from the plunger rod 28. Specifically, the power cylinder is provided at each end with a piston 46 secured on a sleeve 47 (Fig. III). The pistons 46 are arranged respectively above and below the two pairs of ports 31, 32, and are normally spaced an interval from the ends of the cylinder, as shown. Pipes 38 and 39 stand in open communication with a source of steam or air under elevated pressure, conveniently the same source of steam (or compressed air) as supplies the power cylinder 19. It will be noted that the sleeves 47 carry flanges 48 that severally abut upon the stationary cylinder heads 21, 81, and prevent the pistons 46 from moving under steam pressure from the positions in which they are shown. If for any reason the power plunger 28 should travel beyond the normal limits of its range of reciprocation, the piston 20 will strike either one or the other, as the case may be, of the pistons 46. Manifestly, each piston 46 comprises a yielding cylinder head—a shock absorber—that operates to bring the "wild" power plunger gradually to rest, without harm to the stationary cylinder heads, or other parts of the apparatus.

In still further accordance with the invention, I organize with the upper end of the air cylinder 17 a valve-controlled by-pass 49, by virtue

of which the upper end of such cylinder, being normally open to the outer atmosphere, will be automatically closed if the load is suddenly relieved from the plunger rod 28. That is to say, the air cylinder is adapted to serve as a pneumatic shock absorber that cooperates with the upper shock-absorbing piston 46 in the power cylinder 19. The by-pass 40 communicates at its opposite ends with the air cylinder at vertically spaced-apart points 93 and 94, and between such points the by-pass includes a check-valve 90. It is to be noted that both points 93 and 94 lie above the upper limit of the normal range of reciprocation of the piston 18, and that the by-pass includes a branch 91 which, during normal operation of the apparatus, establishes communication between the upper end of the air cylinder and the open atmosphere.

If the drill-rod breaks in service, the plunger assembly 18, 20, 28 is by the air pressure beneath piston 18 driven violently upward, carrying the piston 18 above the point 94 at which the by-pass 40 opens into the air cylinder. Immediately, air at exceedingly high pressure flows from beneath the piston 18 into the lower opening 94 of the by-pass; the by-pass includes a plunger 92, and it will be understood that this air, flowing into the by-pass and surging upward through the check-valve, shoots the plunger 92 upward into a chamber 95 arranged in the by-pass structure above the point 93 at which the by-pass opens into the top of the air cylinder 17. With the plunger 92 in such position, the branch 91 is closed, and a direct line of flow is established from beneath the piston 18 to above, while the check-valve 90 serves to prevent back-surge from above the piston to below. Thus, a body of air is confined above the piston 18, and such confined body of air operates to bring the "runaway" plunger assembly to rest, without harming the apparatus. The pneumatic pressure thus developed in the upper end of the cylinder may, as the piston 18 approaches the head 21, exceed the pressure of the air beneath the piston 18, but as already mentioned the check-valve 90 serves to prevent a back-surge of air through the by-pass 40.

The structure described above admits of many modifications within the skill of the engineer, and it will be understood that, within the terms and intent of the appended claims, such modifications lie in the field of the invention.

I claim as my invention:

1. Apparatus for drilling terrestrial bores including two cylinders supported one above the other in axial alignment, a plunger reciprocable in said cylinders, a tubular drill-rod connected to the lower end of said plunger, a tool-carrier connected to the lower end of said drill-rod, a drill secured to the lower end of said tool-carrier, said tool-carrier comprising two tubular members telescopically movable and forming a vertically extensible and contractible pump chamber communicating with the bore of said tubular drill-rod, resilient means arranged between said telescopic members, and a valve-controlled inlet opening from the lower end of said pump chamber through said drill; a piston secured on said plunger in the lower of said two cylinders, a body of gas confined in said last cylinder beneath said piston, and providing a compressible and expandable medium adapted to sustain the weight of the assembled plunger, drill-rod, tool-carrier and drill, means for injecting gas into such body of gas, means for regulating the effective length

of the cylinder including such body of gas; a power piston secured on said plunger in the upper of said cylinders, said power piston being reciprocable in said upper cylinder for axially vibrating the assembled plunger, drill-rod, tool-carrier and drill sustained by said confined body of gas, and means organized with said cylinders for yieldingly resisting the movement of said plunger beyond the limits of the range of vibration normally effected by said power piston.

2. Apparatus for drilling terrestrial bores including a vertically extending tubular drill-rod mounted for vertical vibration on a compressible and expandable medium, a vertically extending tool-carrier secured to the lower end of said drill-rod, a drill secured to the lower end of said tool-carrier, said tool-carrier including two tubular members telescopically movable relatively to one another and forming a vertically extensible and contractible pump chamber communicating with the bore of said tubular drill-rod, a valve-controlled inlet opening into the bottom of such chamber, and shock-absorbing means arranged between said telescopic members.

3. Apparatus for drilling terrestrial bores including a vertically extending, rotary, tubular drill-rod mounted for vertical vibration on a compressible and expandable medium, a vertically extending tool-carrier secured to the lower end of said drill-rod, a drill secured to the lower end of said tool-carrier, said tool-carrier including two tubular members telescopically and rotatably movable relatively to one another and forming a vertically extensible and contractible pump chamber communicating with the bore of said tubular drill-rod, a valve-controlled inlet opening into the bottom of such chamber, and a spring arranged between said telescopic members, substantially as described.

4. Apparatus for drilling terrestrial bores including a vertically extending drill-rod mounted for vertical vibration on a compressible and expandable medium, a drill, and vertically telescoping means securing said drill to the lower end of said drill-rod.

5. Apparatus for drilling terrestrial bores including a vertically extending, rotatable drill-rod mounted for vertical vibration on a compressible and expandable medium, a vertically extending tool-carrier secured to the lower end of said drill-rod, a drill secured to the lower end of said tool-carrier, said tool-carrier including two members telescopically movable relatively to one another on the axis of the drill-rod, and shock-absorbing means arranged between said members.

6. Apparatus for drilling terrestrial bores including a vertically extending, rotatable drill-rod mounted for vertical vibration on a compressible and expandable medium, a vertically extending tool-carrier secured to the lower end of said drill-rod, a drill secured to the lower end of said tool-carrier, said tool-carrier including two members telescopically and rotatably movable relatively to one another, and a compression and torsion spring arranged between said members.

7. Apparatus for drilling terrestrial bores including a vertically extending, rotatable drill-rod mounted for vertical vibration on a compressible and expandable medium, a vertically extending tool-carrier secured to the lower end of said drill-rod, a drill secured to the lower end of said tool-carrier, said tool-carrier including two tubular members telescopically movable relatively to one another and forming a vertically extensible and contractible pump chamber, and a

valve-controlled inlet opening into the bottom of such chamber.

8. Apparatus for drilling terrestrial bores including a vertically reciprocable drill-carrier including two telescopic members rotatable relatively to one another, a drill, and a spring arranged between said telescopic members, said spring being responsive to compressive and torsional stresses and yieldingly supporting said drill on the lower end of said carrier.

9. Apparatus for drilling terrestrial bores including a tool-carrier, a vertically reciprocable member extending upward from such tool-carrier, a drill secured to the lower end of said carrier, said carrier comprising two hollow members with an interposed spring, said members being telescopically contractible with the aid of spring tension when said drill is driven downward against the work and telescopically extensible against the opposition of spring tension when (under the pull of said reciprocable member) said drill is lifted from the work, and a valve-controlled inlet in the bottom of such hollow tool-carrier, whereby said carrier provides a continuously operating pump during the well-drilling reciprocation of said member.

10. Apparatus for drilling terrestrial bores including a vertically extending, rotary, tubular drill-rod mounted for vertical vibration on a compressible and expansible medium, a reciprocating engine having a piston rod connected to the upper end of said drill-rod, said engine providing energy to maintain said drill-rod in vibration, a vertically extending tool-carrier secured to the lower end of said drill-rod, a drill secured to the lower end of said tool-carrier, said tool-carrier including two tubular members telescopically movable and forming a vertically extensible and contractible pump chamber communicating with the bore of said tubular drill-rod, means for yieldingly resisting and assisting such telescopic movement of said members, and a valve-controlled inlet opening from the lower end of said pump chamber through said drill.

11. Apparatus for drilling terrestrial bores including a vertically extending drill-rod carrying a drill at its lower end, a plunger connected to the upper end of said drill-rod, a power cylinder, said plunger carrying a power piston reciprocable in said cylinder for axially vibrating said plunger and drill-rod assembly, and means for protecting the apparatus from damage in case the drill-rod should break in service, said means including a bumper piston positioned in the upper end of said power cylinder above the upper limit of the normal range of reciprocation of said power piston, and a body of fluid confined above said shock-absorbing piston.

12. Apparatus for drilling terrestrial bores including a vertically extending drill-rod carrying a drill at its lower end, a plunger connected to the upper end of said drill-rod, a power cylinder, said plunger carrying a power piston reciprocable for axially vibrating said plunger and drill-rod assembly, said power cylinder including a stationary cylinder head at each end, a shock-absorbing piston secured in each end of said cylinder, said shock-absorbing pistons being spaced from the respective heads of said cylinder in positions beyond the respective limits of the range of reciprocation of said power piston and a body of fluid confined in the cylinder between each shock-absorbing piston and the companion cylinder head.

13. Apparatus for drilling terrestrial bores including a cylinder, a piston in such cylinder, a body of gas confined in said cylinder beneath said piston, a drill assembly connected to said piston, with the weight of said assembly borne by the body of gas beneath the piston, a body of liquid confined in said cylinder beneath the body of gas therein, and means for varying the depth of said body of liquid, to regulate the effective length of the portion of said cylinder extending below said piston.

14. Apparatus for drilling terrestrial bores including a cylinder, a piston in such cylinder, a body of gas confined in said cylinder beneath said piston, a drill assembly connected to said piston, with the weight of said assembly borne by the body of gas beneath the piston, and means for injecting gas into such body, a body of liquid confined in said cylinder beneath the body of gas therein, and means for varying the depth of said body of liquid, to regulate the effective length of the portion of said cylinder extending below said piston.

15. Apparatus for drilling terrestrial bores including a drill-rod supported at the earth's surface for vertical reciprocation, said drill-rod adapted to extend downward from the earth's surface into the bore being drilled, a drilling tool, means yieldingly supporting said tool upon the end of said drill-rod at the bottom of such bore, and means at the top of such bore opposing the effect of gravity on the drill-rod and tool assembly, said last means being adapted to store energy during the downstroke of the drill-rod and tool to assist in the ensuing upstroke thereof.

16. Apparatus for drilling terrestrial bores including a drill-rod supported at the earth's surface for vertical reciprocation, said drill-rod adapted to extend downward from the earth's surface into the bore being drilled, a drilling tool, means yieldingly supporting said tool upon the end of said drill-rod at the bottom of such bore, and an elastic body of compressed gas confined against flow at the top of such bore and sustaining the weight of said drill-rod and tool assembly, said body of air being adapted to store energy during the downstroke of the said assembly to assist in the ensuing upstroke thereof.

17. Apparatus for drilling terrestrial bores including a cylinder, a piston in such cylinder, a body of gas confined in said cylinder beneath said piston, a drill assembly connected to said piston, with the weight of said assembly borne by the body of gas beneath the piston, the portion of said cylinder above said piston normally communicating with the open atmosphere, and valve means for automatically interrupting such communication, whereby a body of air is confined above the piston, yieldingly to arrest such piston when it moves above the upper limit of its normal range of movement, said valve means comprising a by-pass communicating with said cylinder at vertically spaced apart points above said normal range of piston movement, said by-pass including a check-valve, an outlet opening to the outer atmosphere above said check-valve, and a movable member for closing said outlet in the event that said piston rises above the lower point at which said by-pass communicates with said cylinder.

WILLIAM R. COLEMAN.
